PREPARATION OF LEAD-SODIUM ALLOY AND
TETRAETHYLLEAD

Edwin L. Mattison, Newark, Del., assignor to E. I. du Pont de Nemours & Company, Wilmington, Del., a corporation of Delaware

Application May 2, 1950, Serial No. 159,575

18 Claims. (Cl. 260—437)

This invention relates to the preparation of lead-sodium alloy especially adapted for use in the manufacture of tetraethyl lead and, particularly, to alloy which has increased reactivity toward ethyl chloride.

Prior to my invention, the commonly employed method for making commercial lead-monosodium alloy has been by the batch process. Liquid sodium and liquid lead, in the weight ratio of 1:9, have been fed by gravity from scale tanks into a manufacturing pot provided with an agitator, a jacket for removal of the heat of formation of the alloy, and induction heating to maintain the alloy in molten condition after it is formed; all substantially as disclosed by Amick et al. in Patents 2,043,224 and 2,091,801. When the required proportions of lead and sodium have been alloyed, the molten alloy is pumped to an agitated distribution pot which is also provided with induction heating, and thence to a battery of oil-jacketed casters of the character disclosed by Stetcher in Patent 2,134,091. Such casters are long rectangular chambers in which the alloy is allowed to cool batchwise in relatively thin layers. After the alloy has solidified, the caster is set to vibrating and the alloy is broken up and discharged to a grinder of the character disclosed by Stetcher et al. in Patent 2,047,391. The ground alloy then passes to a vibrating cooler which is similar in construction to the caster. As the ground alloy is cooled, the vibrating feature in the cooler moves it to the discharge port where it is loaded into hoppers. The hoppers must be transported to and connected with the autoclaves in which the tetraethyl lead is manufactured. All of these operations must be performed in an atmosphere of nitrogen or other inert gas.

The alloy is fed from the hoppers into the autoclaves where it is agitated and heated to about 45° C. to about 50° C. Ethyl chloride is then added to the autoclaves and held in contact with the alloy for 2 to about 4 hours to complete the formation of tetraethyl lead by reaction of the ethyl chloride with the lead-sodium alloy. Theoretically, 1 part by weight of ethyl chloride to 3.57 parts of lead-sodium alloy is required. However, in practice, a small excess of ethyl chloride is employed, usually, about 60% excess. Care is taken to maintain the temperatures in the autoclaves below 100° C. because tetraethyl lead tends to decompose rapidly at temperatures slightly above 100° C., and with explosive violence at materially higher temperatures. After the reaction is complete, the excess ethyl chloride is distilled off and the reaction mass is transferred to a steam still where the tetraethyl lead is distilled off.

The prior processes of preparing the alloy and transporting it to the autoclaves are expensive to operate and require elaborate and costly equipment. The alloy is not uniform in size, varying from small chunks to a fine powder, and does not have maximum reactivity toward ethyl chloride, whereby undesirably long periods of time are required to complete the reaction with ethyl chloride. Furthermore, because of the physical condition of the alloy and its slow reactivity, it has been

2

necessary to carry out the reaction with ethyl chloride in batches and to add the alloy to the autoclave prior to the addition of the ethyl chloride. A satisfactory method of adding such solid alloy continuously to a reactor, containing ethyl chloride under pressure, is not known.

It has been proposed, in Patent 2,109,005, to make particles of lead-sodium alloy by cooling the molten alloy to a temperature below that at which particles of the alloy tend to adhere to each other and stirring the mass during such cooling. When properly operated, this gives particles of uniform size. In spite of this advantage, however, such process still has the disadvantages of requiring special, costly equipment and careful blanketing with large quantities of nitrogen and does not lend itself to plant scale operations or to incorporation into a continuous process for making tetraethyl lead.

Nourse, in Patent 2,310,806, has proposed grinding solid lead-sodium alloy in liquid ethyl chloride and reacting such alloy with the ethyl chloride. This and like expedients have resulted in alloy of greatly decreased reactivity and the production of low yields of tetraethyl lead.

Voorhees, in Patent 1,974,167, has proposed the manufacture of gasoline containing lead-hydrocarbon compounds by atomizing molten lead-sodium alloy and dropping it into chlorinated gasoline maintained at 300° F. to 600° F. (148.89° C. to 315.56° C.), whereby the alloy is simultaneously solidified and reacted with the chlorinated hydrocarbons. He thereby obtains complex lead-hydrocarbon compounds, other than tetraethyl lead, which are less effective than tetraethyl lead as anti-knock agents. Such process is impractical because it involves the treatment of large volumes of material at temperatures of at least 300° F., requiring large and expensive equipment, and the reaction with the chlorinated hydrocarbons in such dilute solution is incomplete so that the resulting gasoline will contain objectionably large amounts of corrosive chlorinated compounds.

It is an object of my invention to provide an improved process for preparing lead-sodium alloy in a simple and economical manner which requires relatively simple and inexpensive equipment and overcomes the disadvantages of the prior art processes. Another object is to provide a process for preparing lead-sodium alloy in a form in which it has increased reactivity toward ethyl chloride. Still another object is to provide a process for preparing lead-sodium alloy in particles of uniform and controlled size. A further object is to provide a continuous process for preparing a slurry of lead-sodium alloy in ethyl chloride, particularly adapted for use in a continuous process for making tetraethyl lead and which continuous process of preparing such slurry can be combined in a continuous process for making tetraethyl lead. A still further object is to advance the art. Other objects will appear hereinafter.

The above and other objects may be accomplished in accordance with my invention which comprises passing a stream of molten lead-sodium alloy, containing from 9.9% to 10.1% by weight of sodium, at a temperature of from about 370° C. to about 750° C. through an orifice of less than ½ inch in diameter and then into a violently agitated body of liquid ethyl chloride maintained at a temperature of from about —50° C. to +90° C. in a quenching chamber, employing about 1 part of alloy to from 9 parts to 1 part by weight of ethyl chloride and forming a slurry of unreacted alloy in ethyl chloride in which the alloy is in the form of bright solid particles of a uniform size up to about 8 mesh in size. The resulting lead-sodium alloy particles are ini-

tially unreactive toward ethyl chloride but, after a period of time, are substantially more reactive than alloy prepared by other methods, and are peculiarly adapted for making tetraethyl lead. The slurry, so produced, may then be transferred to a reactor for reaction to produce tetraethyl lead, or the alloy particles may be separated from the ethyl chloride and subsequently employed in the manufacture of tetraethyl lead, the slurry being passed to the reactor or the alloy being separated from the ethyl chloride while the particles of alloy are still bright. Such process may be operated as a batch process or as a continuous process.

It is well known to the art that lead-sodium alloy reacts with ethyl chloride at ordinary temperatures and quite rapidly at higher temperatures, such as 35° C. to 70° C., as shown by Kraus et al., in Patents 1,612,131 and 1,697,245. However, lead-sodium alloy melts at about 366° C. Accordingly, it would be expected that, if molten alloy were added to ethyl chloride, the hot alloy would immediately heat the ethyl chloride in contact therewith to high temperatures with simultaneous reaction, and that, as the addition of the molten alloy was continued, some of the hot alloy would contact tetraethyl lead in vapor or liquid form with resultant decomposition of the tetraethyl lead and, probably, with resultant explosions. However, I have found that such expected results are not obtained if the addition of the molten alloy to the ethyl chloride is accomplished under properly controlled conditions.

I have found that, when a stream of molten alloy is added to a body of violently agitated ethyl chloride maintained at a temperature of 90° C. or below, the alloy is solidified and cooled to the temperature of the ethyl chloride (quenched) in less than 1 second and, probably, less than 0.1 second, without reaction with the ethyl chloride. I have further found that such cooled alloy and the ethyl chloride can be maintained in contact for appreciable periods of time without reaction; i. e., the alloy particles, when first formed, are unreactive toward ethyl chloride but, after a period of time, become highly reactive. Stated another way, there is a well defined induction period at 90° C. and below before reaction between the alloy and the ethyl chloride occurs and during which no reaction takes place. The alloy particles are clean, bright, and silvery in appearance, when first formed, and retain such appearance until reaction with ethyl chloride starts. When such reaction does start, the particles of alloy promptly lose their bright appearance and acquire a black coating. Such induction period varies inversely with the temperature of the slurry, being about 30 seconds at 90° C. and increasing more and more sharply as the temperature is decreased, particularly at temperatures of 35° C. and below. Approximate induction periods in minutes at representative temperatures are shown below:

Temperature, ° C.:	Induction minutes period
13	20+
20	14
30	8
50	3
60	2
90	0.5

The substantially instantaneous quenching of the alloy and the induction period provide sufficient time for the practical formation of the desired slurry and separation of the alloy from the ethyl chloride or passage of the slurry to a reaction vessel, while the particles are still bright and before reaction between the alloy and the ethyl chloride takes place. It is merely necessary to determine the amount of time which will be required to carry out the selected procedure, and then to maintain

the slurry at a temperature having an induction period at least equal to such time.

It is well known to the art that lead-sodium alloy, containing 10% sodium by weight, is the most efficient for the production of tetraethyl lead and gives the highest yields, and that very slight variations in the composition of the alloy seriously decrease its efficiency and the yields of tetraethyl lead. Accordingly, it has been necessary to exercise great care to obtain alloy of such exact composition. However, I have found that lead-sodium alloy, containing from 9.9% to 10.1% by weight of sodium, may be treated by my process to obtain alloy of equal reactivity toward ethyl chloride. Materially wider variations in the composition of the alloy are still deleterious. This permissible variation in the composition of the alloy, while apparently slight, is important as it reduces the necessity for rigid control of the composition of the alloy, whereby alloy of maximum efficiency can be manufactured more easily and economically.

When the ethyl chloride, employed for quenching the alloy, is to be used to react with the alloy to make tetraethyl lead, as when the slurry is passed to a reactor, it will, preferably, contain a small proportion of an accelerator of the reaction of the character disclosed in Patents 2,426,598, 2,464,397, 2,464,398, 2,464,399 and 2,477,465. The preferred accelerator is acetone which will be employed in the proportion of about 0.1% by weight based on the ethyl chloride. The presence of such accelerator does not materially reduce the induction periods hereinbefore disclosed under the conditions of my process.

It is well known that lead-sodium alloy is reactive to oxygen and moisture and hence it is conventional practice to protect the alloy by an atmosphere of an inert gas, such as nitrogen and helium. It will be understood that such conventional practice is followed in my process. Before introduction into the ethyl chloride and after separation therefrom, the alloy is conventionally protected by an atmosphere of such an inert gas. During the quenching and subsequent steps, the alloy is protected by liquid ethyl chloride and vapors thereof above the liquid, which may be supplemented by nitrogen or other inert gas, particularly where gas pressure is desirable for forcing the slurry through pipes and the like.

The process may be carried out in various ways and in various types of equipment. A simple method comprises placing the ethyl chloride in a quenching chamber in the form of a vessel equipped with mechanical stirring means and, preferably, with a reflux condenser, stirring the ethyl chloride to give it a velocity between 25 and 1000 feet per minute, and passing a stream of molten alloy into the agitated body of ethyl chloride. The temperature of the ethyl chloride throughout the process is conveniently regulated by refluxing of the ethyl chloride and, for this purpose, the equipment is maintained under a pressure determined by the temperature desired. The rate of addition of the alloy is also adjusted according to the desired temperature of the slurry so that all of the alloy is added in materially less than the induction period for such temperature. After the addition of the alloy is completed, the agitation is stopped, whereby the alloy rapidly settles to the bottom of the vessel. Then most of the ethyl chloride is decanted off and the rest is removed from the alloy by evaporation. The evaporation of the ethyl chloride will usually be accompanied and aided by passing an inert gas, such as nitrogen and helium, through the vessel and, preferably, through the bed of alloy, so as to replace the ethyl chloride with the inert gas. The entire process is completed within the induction period for the temperature of the ethyl chloride.

When the temperature is regulated by the boiling of the ethyl chloride, the following table may be used to

determine the pressure at which the system is to be maintained to obtain substantially the temperature desired.

Temperature, ° C.:	Pressure, lbs. per sq. in. absolute
-50	0.6
-40	1.2
-30	2.2
-20	3.6
-10	5.8
0	9.0
+10	13
+20	19
+30	27
+40	38
+50	51
+60	65
+70	84
+80	107
+90	137

In the method just described, the ethyl chloride will usually be maintained at 30° C. or below so that the induction period will be of a length to provide sufficient time for ready completion of the process and separation of the ethyl chloride from the alloy while the alloy particles are still bright. Temperatures below -50° C. may be used, but will usually be economically impractical. More than 9 parts by weight of ethyl chloride to each part of lead-sodium alloy may be used, but usually will be uneconomical and inefficient because of the large excesses of ethyl chloride to be handled and recovered. Less than 1 part of ethyl chloride for each part of lead-sodium alloy renders the slurry so thick that efficient agitation is quite difficult. Preferably, I employ from about 2 to about 4 parts by weight of ethyl chloride to each part of lead-sodium alloy.

The temperature of the ethyl chloride during such process may be controlled by methods other than refluxing of the ethyl chloride. It may be controlled, wholly or in part, by passing a cooling fluid over the outer surface of the quenching vessel or through cooling coils immersed in the ethyl chloride. In many cases, it is preferred to maintain a pressure well above that at which boiling will occur and to control the temperature by the initial temperatures of the alloy and the ethyl chloride. The temperatures and pressures involved are moderate. Usually, the temperature is controlled by having the initial temperature of the ethyl chloride lower than the desired temperature of the slurry by an amount such that the heat of the alloy will be absorbed by the ethyl chloride without boiling and bring the slurry to the desired final temperature.

The alloy has a heat of fusion of only 8.1 calories per gram and a heat capacity of only 0.056 calorie per gram per °C. Ethyl chloride has a heat capacity of 0.368 calorie per gram per °C. Therefore, the required initial temperature of the ethyl chloride may be readily calculated by those skilled in the art according to the formula

$$\frac{8.1 + 0.056(T_a - T_s)}{0.368E} = T_s - T_e$$

wherein T_a represents the initial temperature of the alloy, T_s represents the final temperature of the slurry, E represents the parts by weight of ethyl chloride for each part of alloy, and T_e represents the initial temperature of the ethyl chloride. Representative calculated increases in the temperature of the ethyl chloride, produced by quenching molten alloy at 430° C. in various amounts of ethyl chloride, and required initial temperatures of the ethyl

chloride, to obtain a slurry temperature of substantially 30° C., are shown in the following table:

Parts Ethyl Chloride Per Part Alloy	Increase in Temperature (° C.)	Initial Temperature, Ethyl Chloride (° C.)
9	9.2	+20.8
4	20.7	+9.3
3	27.6	+2.4
2	41.4	-11.4
1	82.8	-52.8

Such calculated figures correspond well with those obtained in practice.

The size of the particles of alloy produced is dependent, mainly, upon the violence with which the ethyl chloride and stream of molten alloy come into contact and, to a lesser extent, upon the diameter of the stream of alloy. The diameter of the alloy stream entering the liquid ethyl chloride should not be larger than substantially 1/2 inch and, usually, will be less. The size of the molten alloy stream is controlled by passing it through an orifice of less than 1/2 inch in diameter and, preferably, less than 1/8 inch in diameter. The minimum size of orifice, which can be employed, is dependent solely upon ability to force the molten alloy through it at the desired rate without clogging, and, appears to be about 1/32 inch. Obviously, molten alloy streams of more than 1/8 inch in diameter require more violent contact with the ethyl chloride than streams of smaller diameter in order to obtain alloy particles of corresponding size. The orifice and feeding means containing it, such as a nozzle, will be out of contact with the liquid ethyl chloride so as to avoid freezing of the molten alloy before the alloy has passed through the orifice.

The violence with which the ethyl chloride contacts the stream of molten alloy is dependent upon the violence of the agitation. The particle size decreases with increase in the violence of agitation or velocity of the ethyl chloride in which the alloy is quenched. When the stream of molten alloy is less than about 1/8 inch, the average size of the solid alloy particles will vary roughly from about 8 mesh to about 100 mesh as the linear velocity of the ethyl chloride is varied from about 25 to about 500 feet per minute. Alloy particles of about 10 to about 40 mesh will usually be obtained at linear velocities of from about 50 to about 250 feet per minute and particles of from about 10 to about 20 mesh at linear velocities of from about 50 to about 130 feet per minute. Higher linear velocities up to about 1000 feet per minute may be used, particularly with molten alloy streams of more than 1/8 inch diameter. While the reactivity of the alloy does not appear to vary materially with variation in the particle size up to about 8 mesh, it is preferred that the alloy have a particle size of from about 10 mesh to about 40 mesh, particularly from about 10 mesh to about 20 mesh, because of convenience in physical handling.

The agitation of the ethyl chloride, during the quenching, may be produced by means other than mechanical stirring. Sufficient agitation may often be obtained by injecting the molten alloy into the ethyl chloride at a rate sufficient to cause the ethyl chloride to boil violently. The stream of alloy may be introduced into a flowing stream of ethyl chloride. Also, the ethyl chloride may be injected into the quenching vessel in one or more streams at high velocity, preferably, tangentially of the vessel, and injecting the stream of molten alloy into the whirling ethyl chloride substantially simultaneously, particularly as will be described in more detail hereinafter in connection with the continuous process and the accompanying drawings. By maintaining the rate of feed and velocity of the streams of alloy and ethyl chloride substantially constant during the quenching, alloy of substantially uniform particle size is obtained.

Other methods of separating the alloy from the ethyl chloride may be employed, such as by evaporation of all of the ethyl chloride or by filtration. The separation need not be accomplished in the quenching vessel, as the slurry may be caused to flow from the quenching vessel to a filter or to a separate settling tank or tanks and the alloy then passed to dryers, for batch or continuous operation.

Preferably, the process will be carried out continuously and particularly as part of a continuous process for making tetraethyl lead. In such continuous process, the ethyl chloride is continuously added to the quenching vessel or chamber and the slurry continuously removed from the quenching chamber substantially as fast as it is formed and passed to equipment for continuously separating the alloy from the ethyl chloride, such as filters or one or more settling and decanting tanks and evaporators, or to one or more reactors, while the alloy particles are still bright.

In such continuous process, the pressure in the quenching chamber will preferably be maintained well above that which would permit boiling of the ethyl chloride, usually about 50 to about 100 pounds above, and the temperature will be controlled by means other than refluxing of the ethyl chloride. The temperature of the slurry may be controlled conveniently by passing a cooling liquid over the outside of the quenching chamber or through cooling coils in contact with the ethyl chloride in the quenching chamber. Preferably, however, the temperature of the slurry is controlled by supplying the ethyl chloride at a lower initial temperature so that the heat absorbed thereby in the quenching will produce the desired temperature in the slurry according to the principles hereinbefore described, the necessary temperatures being determined according to the formula hereinbefore given. Such two methods of controlling the temperature of the slurry will frequently be combined, the temperature being controlled, in part, by absorption of heat by the ethyl chloride to raise its temperature and, in part, by the application of a separate cooling fluid.

When the slurry is to be conducted directly from the quenching chamber to a reaction chamber for reaction to make tetraethyl lead, the temperatures will usually be controlled so that the slurry has a temperature of from about 50° C. to 90° C., and, preferably, a temperature of from about 50° C. to about 60° C. The induction periods at these temperatures are sufficiently long to permit the slurry to be conducted to the reaction chamber while the alloy particles are still bright and before reaction takes place, since such conduction can usually be accomplished readily in from about 1 to about 5 seconds. Preferably, the reaction, between the alloy and the ethyl chloride to produce tetraethyl lead, will be carried out at temperatures of from about 85° C. to about 95° C. and, if the slurry is at a lower temperature when it reaches the reaction chamber, it will be heated therein to such reaction temperature.

Also, in the continuous process, it is preferred to employ a circular quenching chamber and to inject the ethyl chloride therein in one or more high velocity streams tangent to the quenching chamber. It is also preferred to use from about 2 to about 9 parts by weight of ethyl chloride to each part of alloy, and, particularly, from about 2 to about 6 parts of ethyl chloride, so as to provide slurries containing from about 14% to about 33% alloy and which are sufficiently fluid to flow readily through pipes to the separating equipment or the reactor. Furthermore, it is preferred to regulate the velocity of the ethyl chloride so as to produce slurries in which the alloy has a particle size of from about 8 mesh to about 40 mesh, especially from about 10 mesh to about 20 mesh, as such slurries have particularly desirable flow characteristics. Also, it is preferred to employ an orifice of less than $\frac{1}{8}$ inch in diameter for forming the stream of molten alloy to be injected into the ethyl chloride.

A representative type of apparatus, which I have found to be particularly effective for carrying out the continuous process, is shown in the accompanying drawings in which:

5 Fig. 1 is a somewhat diagrammatic view of one suitable form of apparatus for the continuous production of a slurry of lead-sodium alloy in ethyl chloride and passing it to a reactor for the continuous manufacture of tetraethyl lead;

10 Fig. 2 is a vertical sectional view of the quenching apparatus; and

Fig. 3 is an enlarged horizontal sectional view taken on line 3—3 of Fig. 2, with parts broken away for clearness of illustration.

15 Referring first to Figure 1, a quenching chamber 10 is connected at its lower end with a pipe 12 for conducting the slurry into the reactor 14. The reactor is provided with a jacket 16, having an inlet 18 and an outlet 20, for circulation of a heat exchange fluid over the outer surface of the reactor. At the exit end of the reactor, there is a pipe 22, provided with a valve 24, for discharge of the heavy products of the reaction mixture to the receiver 30 and a pipe 26, provided with a valve 28, for drawing off excess ethyl chloride and passing it to the receiver 30.

20 Referring more particularly to Figures 2 and 3, the quenching chamber 10 is in the form of a cone having its apex at the bottom. As shown, the quenching chamber is about 6 inches in height and has an internal diameter of about 4 inches at its upper end 32 and an outlet 34 about $\frac{3}{4}$ inch in diameter. The quenching chamber is provided with a flange 36 at its lower end which is bolted to the flange 38 at the upper end of the pipe 12. The quenching chamber is also provided with a flange 40 at its upper end which is bolted to a flange 42 at the lower end of a housing 48. A liquid ethyl chloride supply pipe 44 is provided adjacent the upper end of the quenching chamber and terminates in three small ports 46 at its junction with the inner wall of the cone. The ethyl chloride supply pipe 46 is positioned tangentially to the inner surface of the cone and the ports 46 are arranged with their centers in a line corresponding to a generatrix of the cone, as is particularly shown in Figure 3.

25 The valve and nozzle assembly for feeding alloy to the quenching chamber comprises a vertical cylindrical housing 48 having its axis positioned to one side of the axis of the quenching chamber 10. A nozzle 50 is positioned coaxially of the housing 48, for feeding molten alloy to the quenching chamber. Such nozzle 50 terminates at its lower end in a restricted orifice 52 which, as shown, has a diameter of about $\frac{3}{32}$ inch. The nozzle is also provided with a rod 54 secured to the lower end of the valve 56. The rod 54 has a diameter materially less than the bore of the nozzle but slightly greater than the orifice 52, and a lower end of reduced diameter slightly less than the diameter of the orifice 52. The rod 54 is provided so that, when the valve is closed, the lower end of the rod will pass through the orifice 52 and close such orifice, but, when the valve is opened, the rod is moved out of the orifice so as to permit flow of molten alloy therethrough. This rod is provided primarily for removing any material which may clog the orifice, in whole or in part, during operation which is accomplished by momentarily closing the valve, thus forcing the rod through the orifice and pushing any obstruction before it.

30 The valve 56 is provided, at its upper end, with a hand-wheel 58 for operation of the valve. The valve 56 is also threaded, at its upper end, to engage corresponding inner threads in the upper end of the valve bonnet 60.

35 The valve bonnet contains packing material 62 and a packing gland 63 regulated by a packing nut 64. The lower end of the valve 56 engages the valve seat 66 at the upper end of the nozzle 50. A disc 68 is secured to the upper end of the nozzle 50 and surrounds the lower end of the valve 56. Such disc is provided with a central

enlarged valve chamber 70 connecting with the bore of the nozzle 50. The disc also has an inlet 72 extending through one side thereof into the valve chamber 70, which inlet 72 is connected at its outer end with a molten alloy supply pipe 74. The housing 48 is provided at its upper end with a flange 76 which is bolted to a flange 78 at the lower end of the valve bonnet 60 for securing the housing 48, the disc 68 and the valve bonnet 60 together.

A nitrogen supply pipe 80 is connected with the housing 48 near the lower end thereof and adjacent the orifice 52. As shown particularly in Figure 3, the nitrogen supply pipe 80 is connected with the housing 48 so as to direct the nitrogen substantially tangentially of the inner surface of the housing 48. Preferably, the nozzle 50 is heated inductively by an alternating current flowing through a winding (not shown) outside the housing 48 so as to prevent freezing of the molten alloy in the nozzle.

In operation, liquid ethyl chloride at the desired temperature is injected under pressure into the quenching chamber 10 through pipe 44 and ports 46 to form a rapidly whirling vortex of liquid ethyl chloride of appreciable depth, preferably, filling the cone to a depth of from about $\frac{1}{2}$ to about $\frac{3}{4}$ of the distance from the outlet 34 to the ports 46. With a cone quenching chamber of the dimensions hereinbefore given, the liquid ethyl chloride must be fed at the rate of at least 6.6 pounds per minute in order to provide and maintain the desired vortex. The ethyl chloride may be fed at a rate of from 6.6 pounds per minute to about 12 pounds per minute but, preferably, is fed at a rate of from 6.6 pounds per minute to about 10 pounds per minute. While not necessary, it is generally preferred to introduce an inert gas, such as nitrogen or helium, under pressure through the pipe 80 so as to provide an inert atmosphere in the pipe 48 and prevent contact of the hot molten alloy with vapors of ethyl chloride in this region and to maintain the desired pressure in the quenching chamber.

After the vortex of liquid ethyl chloride has been established in the quenching chamber 10, the valve 56 is opened and molten alloy is introduced through pipe 74, inlet 72, nozzle 50 and orifice 52, whereupon it drops into the rapidly whirling vortex of liquid ethyl chloride to one side of the center of the vortex and is substantially instantaneously solidified and cooled in the form of small pellets. Within a small period of time, estimated to be less than one second, from the contact of the molten alloy with the liquid ethyl chloride, the solidified cooled particles of alloy pass through the outlet 34 as a slurry in ethyl chloride with a whirling motion. Such slurry passes through the pipe 12 and into the reactor 14 in a period of from about 1 to about 5 seconds.

In order to more clearly illustrate my invention, preferred modes of carrying the same into effect and the advantageous results to be obtained thereby, the following examples are given:

Example 1

A one liter round-bottomed flask was provided with a paddle stirrer, a reflux condenser cooled to -60° C. having a drying tube at its upper end, and a heated dropping funnel having a $\frac{1}{16}$ inch orifice. 400 grams of ethyl chloride were placed in the flask and maintained at a temperature of about 13° C. by refluxing. The refluxing of the ethyl chloride displaced all oxygen and water vapor from the flask and condenser and maintained an atmosphere of ethyl chloride therein. 60 grams of lead-sodium alloy, containing 10% by weight of sodium, was added to the dropping funnel and melted, while being protected by a blanket of dry nitrogen. The liquid ethyl chloride was stirred rapidly to give it a linear velocity of about 250 feet per minute directly under the end of the dropping funnel which was about 4 inches above the surface of the liquid. The molten alloy, at a temperature of from about 375° C. to about 400° C., was dropped

into the agitated liquid ethyl chloride in a slow stream during a period of about 0.5 minute. When the addition of the alloy was completed, the stirring was stopped, the alloy particles settled, the layer of liquid ethyl chloride decanted off, and the remainder of the ethyl chloride removed by evaporation in a stream of dry nitrogen. The alloy particles were bright in appearance and of a uniform particle size of about 40 mesh. By increasing the linear velocity of the liquid ethyl chloride to 500 feet per minute, alloy of a uniform particle size of about 100 mesh was obtained. When the velocity of the ethyl chloride was decreased to 50 feet per minute, the alloy had a uniform particle size of about 8 mesh.

In order to test the suitability of alloy for making tetraethyl lead, cooled tared bombs were flushed with dry nitrogen, and then, while preventing contamination with air or moisture, 300 grams of ethyl chloride, containing 0.1% of acetone as a catalyst, and 50 grams of alloy were added to the bombs and the bombs immediately sealed. The bombs were quickly heated to reaction temperatures of from 85° C. to 100° C. with agitation, usually by rotating the bombs at about 36 revolutions per minute. When the heating had been conducted for the desired period of time, the reaction was stopped, usually by plunging the bomb into a bucket of ice, the bomb opened, and the contents separated and analyzed to determine the percent yield of tetraethyl lead based on the amount of alloy used.

When the alloy, prepared as described in the first paragraph of this Example 1, was so tested, it produced from about 82% to about 89% yields of tetraethyl lead (an average yield of about 85%) when heated for 5 minutes at reaction temperatures of 85° C. and 90° C. Variation of the particle size of the alloy, between 8 mesh and 100 mesh, produced little or no change in the yield of tetraethyl lead.

Example 2

Lead-sodium alloy, containing 10% by weight of sodium, was quenched in ethyl chloride in the apparatus shown in the accompanying drawing, provided with means (not shown) for taking samples of the slurry issuing from the quenching chamber. Liquid ethyl chloride, at a temperature of 32° C., was pumped under pressure into the quenching chamber at the rate of 9.9 pounds per minute. Molten alloy, at a temperature of 450° C., was injected under pressure through the nozzle into the quenching chamber and into the whirling body of ethyl chloride at the rate of 3.14 pounds per minute. Nitrogen under pressure was introduced in a slow stream sufficient to maintain a nitrogen atmosphere above the whirling body of ethyl chloride and, particularly, around the nozzle and tip, and passed through the outlet with the slurry. The absolute pressure in the quenching chamber was maintained at about 140 pounds per square inch, which was sufficient to prevent vaporization of the ethyl chloride. The total time of the alloy in the quenching chamber was estimated at less than one second. The resulting slurry had a temperature of 57° C. and contained 24% by weight of alloy in the form of small spherical or ovaloid particles which were bright and silvery in appearance and had a particle size mainly in the range of 10 to 20 mesh, at least 90% passing through a 10 mesh screen. The resulting alloy had a reactivity similar to that of Example 1.

The slurry passed from the quenching chamber to the reactor in from about 1 to about 5 seconds and while the alloy particles were still bright and silvery in appearance. The slurry was retained in the reactor and heated to about 90° C. for the rest of the induction period and until substantially all of the alloy was consumed by reaction with the ethyl chloride. The reaction mass issued from the reactor continuously and was passed to the receiver for recovery of the tetraethyl lead, sodium chloride, ethyl chloride, and metallic lead.

The process of Example 2 was repeated many times, varying the alloy feed rate over the range of from 2.25 to 3.7 pounds per minute and the ethyl chloride feed rate over the range of from 7.7 to 8.6 pounds per minute to produce slurries containing from 20.7% to 31.1% by weight of alloy; and also varying the alloy feed rate over the range of from 1.9 to 2.2 pounds per minute and the ethyl chloride feed rate over the range of from 10.1 to 6.6 pounds per minute to produce slurries containing from 15.8% to 25% by weight of alloy. Such slurries gave yields of tetraethyl lead of from 74.5% to 92% in 3 to 17 minutes at 90° C. in the presence of 0.1% of acetone based on the ethyl chloride, an average yield of about 83%.

Example 3

Commercial lead-sodium alloy, containing 10% by weight of sodium, was sieved under nitrogen to obtain a fraction having a particle size of 10 to 16 mesh. When tested with ethyl chloride, containing 0.1% acetone, at 90° C. by the procedure of Example 1, the yields of tetraethyl lead were 74% to 81% in 5 minutes and 83.5% to 90% in 15 minutes. The alloy, which passed through the 16 mesh screen, gave tetraethyl lead yields of about 21% in 15 minutes under the same conditions. The original unsieved alloy gave yields of tetraethyl lead averaging about 76% in 15 minutes under such conditions.

Example 4

Equal quantities of molten lead-sodium alloy, containing 10% by weight of sodium, were put into three bombs, two of which had been previously filled with clean 1/2 steel ball bearings, and solidified. The bombs, containing the ball bearings, were rotated for 16 hours in order to cause the ball bearings to grind the solidified alloy. It was found that this reduces most of the alloy to a fine powder but leaves about 10% not ground. Equal quantities of ethyl chloride, containing 0.1% acetone, were then added to the three bombs and the bombs heated to 90° C. for five minutes. The alloy, ground by the ball bearings, gave yields of 70.35% and 56.4% tetraethyl lead. The unground alloy gave a yield of 86.5% tetraethyl lead.

Example 5

Samples of finely divided lead-sodium alloy, containing 10% by weight of sodium, were prepared by grinding commercial alloy in a micropulverizer while being blanketed under protective atmospheres of helium, dry nitrogen, and ethyl chloride, respectively. About 89% of the alloy, so ground, could be passed through a 250 mesh screen. When tested under the conditions of Example 3, the alloy ground under helium gave yields of 13% to 31.2% tetraethyl lead; that ground under nitrogen gave yields of 22.9% to 35.5% tetraethyl lead; and that ground under ethyl chloride gave yields of 62.3% to 75.2% tetraethyl lead. When the reaction time was reduced to 5 minutes with the alloy ground under ethyl chloride, the yields of tetraethyl lead were 47.1% to 50%.

Examples 3, 4 and 5 are included for purposes of comparison.

It will be understood that the preceding examples have been given for illustrative purposes solely and that my invention is not limited to the specific embodiments disclosed therein, but that I intend to cover my invention broadly as in the appended claims. It will be readily apparent to those skilled in the art that many variations and modifications may be made in the methods and apparatus for carrying out the process of my invention. It will be particularly apparent that the apparatus, shown in the drawings, may be widely varied in size and in construction. Furthermore, the proportions and conditions of operation may be widely varied within the ranges

broadly disclosed without departing from the spirit or scope of my invention.

It will be seen that my invention provides a novel method for preparing lead-sodium alloy in a form which is peculiarly adapted for use in the manufacture of tetraethyl lead. My process is far more simple and requires less elaborate and costly equipment than the process previously employed, whereby the alloy may be prepared in desired form much more readily and economically. By my process, the alloy can be obtained in particles of uniform and controlled size which are materially more reactive toward ethyl chloride and produces higher yields of tetraethyl lead than alloy obtained by the prior processes. Furthermore, my process can be operated most readily in a continuous manner particularly for the production of a slurry of alloy in ethyl chloride which is well adapted for use in the continuous manufacture of tetraethyl lead. Also, my process avoids contact of the hot alloy with tetraethyl lead and thus eliminates danger of explosions from such cause. Therefore, it will be apparent that my invention constitutes a very valuable and important improvement and advance in the art.

I claim:

1. The process which comprises passing a stream of molten lead-sodium alloy, containing from 9.9% to 10.1% by weight of sodium, at a temperature of from about 370° C. to about 750° C. through an orifice of less than 1/2 inch in diameter and then into a violently agitated body of liquid ethyl chloride maintained at a temperature of from about -50° C. to +90° C. in a quenching chamber, employing about 1 part of alloy to from 9 parts to 1 part by weight of ethyl chloride and forming a slurry of unreacted alloy in ethyl chloride in which the alloy is in the form of bright solid particles up to about 8 mesh in size.

2. The process which comprises passing a stream of molten lead-sodium alloy, containing from 9.9% to 10.1% by weight of sodium, at a temperature of from about 370° C. to about 750° C. through an orifice of less than 1/2 inch in diameter and then into a violently agitated body of liquid ethyl chloride maintained at a temperature of from about -50° C. to +90° C. in a quenching chamber, employing about 1 part of alloy to from 9 parts to 1 part by weight of ethyl chloride and forming a slurry of unreacted alloy in ethyl chloride in which the alloy is in the form of bright solid particles of from about 8 mesh to about 100 mesh in size, and then removing at least the solid alloy particles from the quenching chamber while they are still bright.

3. The process which comprises passing a stream of molten lead-sodium alloy, containing from 9.9% to 10.1% by weight of sodium, at a temperature of from about 370° C. to about 750° C. through an orifice of less than 1/2 inch in diameter and then into a violently agitated body of liquid ethyl chloride maintained at a temperature of from about -50° C. to +90° C. in a quenching chamber, employing about 1 part of alloy to from 9 parts to 1 part by weight of ethyl chloride and forming a slurry of unreacted alloy in ethyl chloride in which the alloy is in the form of bright solid particles up to about 8 mesh in size, and then separating the solid alloy particles from the ethyl chloride while they are still bright.

4. The process which comprises passing a stream of molten lead-sodium alloy, containing from 9.9% to 10.1% by weight of sodium, at a temperature of from about 370° C. to about 750° C. through an orifice of less than 1/2 inch in diameter and then into a violently agitated body of liquid ethyl chloride maintained at a temperature of from about -50° C. to +90° C. in a quenching chamber, employing about 1 part of alloy to from 9 parts to 1 part by weight of ethyl chloride and adding the alloy at a rate such that all of it is passed into the ethyl chloride in a period of time materially less than the induction period for the maximum temperature attained by the mixture, forming a slurry of

unreacted alloy in ethyl chloride in which the alloy is in the form of bright solid particles of from about 8 mesh to about 100 mesh in size, then terminating the agitation and separating the solid alloy particles from the ethyl chloride while they are still bright.

5. The process which comprises passing a stream of molten lead-sodium alloy, containing from 9.9% to 10.1% by weight of sodium, at a temperature of from about 370° C. to about 750° C. through an orifice of less than $\frac{1}{2}$ inch in diameter and then into a violently agitated body of liquid ethyl chloride maintained at a temperature of from about -50° C. to about +30° C. in a quenching chamber, employing about 1 part of alloy to from 9 parts to 1 part by weight of ethyl chloride and adding the alloy at a rate such that all of it is passed into the ethyl chloride in a period of time materially less than the induction period for the maximum temperature attained by the mixture, forming a slurry of unreacted alloy in ethyl chloride in which the alloy is in the form of bright solid particles of from about 8 mesh to about 100 mesh in size, then terminating the agitation and separating the solid alloy particles from the ethyl chloride while they are still bright.

6. The process which comprises passing a stream of molten lead-sodium alloy, containing from 9.9% to 10.1% by weight of sodium, at a temperature of from about 370° C. to about 750° C. through an orifice of less than $\frac{1}{2}$ inch in diameter and then into a violently agitated body of liquid ethyl chloride maintained at a temperature of from about -50° C. to +90° C. in a quenching chamber, employing about 1 part of alloy to from 9 parts to 1 part by weight of ethyl chloride and forming a slurry of unreacted alloy in ethyl chloride in which the alloy is in the form of bright solid particles up to about 8 mesh in size, and then passing the slurry to a reaction chamber while the solid alloy particles are still bright.

7. The process which comprises passing a stream of molten lead-sodium alloy, containing from 9.9% to 10.1% by weight of sodium, at a temperature of from about 370° C. to about 750° C. through an orifice of less than $\frac{1}{8}$ inch in diameter and then into a violently agitated body of liquid ethyl chloride maintained at a temperature of from about -50° C. to +90° C. in a quenching chamber, employing about 1 part of alloy to from 9 parts to 2 parts by weight of ethyl chloride and forming a slurry of unreacted alloy in ethyl chloride in which the alloy is in the form of bright solid particles of from about 8 mesh to about 100 mesh in size, and then passing the slurry to a reaction chamber while the solid alloy particles are still bright.

8. The process which comprises passing a stream of molten lead-sodium alloy, containing from 9.9% to 10.1% by weight of sodium, at a temperature of from about 370° C. to about 750° C. through an orifice of less than $\frac{1}{8}$ inch in diameter and then into a violently agitated body of liquid ethyl chloride maintained at a temperature of from about 50° C. to 90° C. in a quenching chamber, employing about 1 part of alloy to from 9 parts to 2 parts by weight of ethyl chloride and forming a slurry of unreacted alloy in ethyl chloride in which the alloy is in the form of bright solid particles of from about 8 mesh to about 100 mesh in size, and then passing the slurry to a reaction chamber while the solid alloy particles are still bright.

are still bright.

9. The process which comprises passing a stream of molten lead-sodium alloy, containing from 9.9% to 10.1% by weight of sodium, at a temperature of from about 370° C. to about 750° C. through an orifice of less than $\frac{1}{8}$ inch in diameter and then into a violently agitated body of liquid ethyl chloride maintained at a temperature of from about 50° C. to about 60° C. in a quenching chamber, employing about 1 part of alloy to from 9 parts to 2 parts by weight of ethyl chloride and forming a slurry of unreacted alloy in ethyl chloride in which the alloy

is in the form of bright solid particles of from about 8 mesh to about 100 mesh in size, and then passing the slurry to a reaction chamber while the solid alloy particles are still bright.

5   10. The process which comprises continuously introducing a high velocity stream of liquid ethyl chloride at a temperature of from about -50° C. to $+80^{\circ}$ C. tangentially into a quenching chamber having a restricted bottom outlet to form a rapidly whirling vortex of liquid ethyl chloride, injecting a stream of molten lead-sodium alloy, containing from 9.9% to 10.1% by weight of sodium, at a temperature of from about 370° C. to about 750° C. through an orifice of less than $\frac{1}{2}$ inch in diameter and then into the body of ethyl chloride to one side of the center of the vortex in the proportion of about 1 part of alloy to from 9 parts to 2 parts by weight of ethyl chloride while maintaining the ethyl chloride in the liquid state at a temperature of from about -50° C. to $+90^{\circ}$ C., and continuously removing the resulting slurry of solid alloy particles in ethyl chloride through the outlet substantially as fast as it is formed and while the alloy particles are still bright.

11. The process which comprises continuously introducing a high velocity stream of liquid ethyl chloride at 25 a temperature of from about -50° C. to $+80^{\circ}$ C. tangentially into a quenching chamber having a restricted bottom outlet to form a rapidly whirling vortex of liquid ethyl chloride, injecting a stream of molten lead-sodium alloy, containing from 9.9% to 10.1% by weight of 30 sodium, at a temperature of from about 370° C. to about 750° C. through an orifice of less than $\frac{1}{8}$ inch in diameter and then into the body of ethyl chloride to one side of the center of the vortex in the proportion of about 1 part of 35 alloy to from 9 parts to 2 parts by weight of ethyl chloride while maintaining the ethyl chloride in the liquid state at a temperature of from about -50° C. to $+90^{\circ}$ C., and continuously removing the resulting slurry of alloy particles in ethyl chloride through the outlet substantially 40 as fast as it is formed, and separating the alloy particles from the ethyl chloride while they are still bright.

45 12. The process which comprises continuously introducing a high velocity stream of liquid ethyl chloride at a temperature of from about -50° C. to $+80^{\circ}\text{ C.}$ tangentially into a quenching chamber having a restricted bottom outlet to form a rapidly whirling vortex of liquid ethyl chloride, injecting a stream of molten lead-sodium alloy, containing from 9.9% to 10.1% by weight of sodium, at a temperature of from about 370° C. to about 750° C. through an orifice of less than $\frac{1}{2}$ inch in diameter and then into the body of ethyl chloride to one side of the center of the vortex in the proportion of about 1 part of alloy to from 9 parts to 2 parts by weight of ethyl chloride while maintaining the ethyl chloride in the liquid state at a temperature of from about -50° C. to $+90^{\circ}\text{ C.}$, and continuously removing the resulting slurry of alloy particles in ethyl chloride through the outlet substantially as fast as it is formed, and continuously passing the slurry directly to a reaction chamber while the particles of alloy are still bright.

60 13. The process which comprises continuously introducing a high velocity stream of liquid ethyl chloride at a temperature of from about 50° C. to 80° C. tangentially into a quenching chamber having a restricted bottom outlet to form a rapidly whirling vortex of liquid ethyl chloride, injecting a stream of molten lead-sodium alloy, containing from 9.9% to 10.1% by weight of sodium, at a temperature of from about 370° C. to about 750° C. through an orifice of less than $\frac{1}{2}$ inch in diameter and then into the body of ethyl chloride to one side of the center of the vortex in the proportion of about 1 part of alloy to from 9 parts to 2 parts by weight of ethyl chloride while maintaining the ethyl chloride in the liquid state at a temperature of from about 50° C. to 90° C., and continuously removing the resulting slurry of alloy particles in ethyl chloride through the outlet substantially as

fast as it is formed, and continuously passing the slurry directly to a reaction chamber while the particles of alloy are still bright.

14. The process which comprises continuously introducing a high velocity stream of liquid ethyl chloride at a temperature of from about -50° C. to $+80^{\circ}$ C. tangentially into a quenching chamber having a restricted bottom outlet to form a rapidly whirling vortex of liquid ethyl chloride, injecting a stream of molten lead-sodium alloy, containing from 9.9% to 10.1% by weight of sodium, at a temperature of from about 370° C. to about 750° C. through an orifice of less than $\frac{1}{8}$ inch in diameter and then into the body of ethyl chloride to one side of the center of the vortex in the proportion of about 1 part of alloy to from 6 parts to 2 parts by weight of ethyl chloride while maintaining the ethyl chloride in the liquid state at a temperature of from about -50° C. to $+90^{\circ}$ C., and continuously removing the resulting slurry of alloy particles in ethyl chloride through the outlet substantially as fast as it is formed, and continuously passing the slurry directly to a reaction chamber while the particles of alloy are still bright.

15. The process which comprises continuously introducing a high velocity stream of liquid ethyl chloride at a temperature of from about 50° C. to 80° C. tangentially into a quenching chamber having a restricted bottom outlet to form a rapidly whirling vortex of liquid ethyl chloride, injecting a stream of molten lead-sodium alloy, containing from 9.9% to 10.1% by weight of sodium, at a temperature of from about 370° C. to about 750° C. through an orifice of less than $\frac{1}{8}$ inch in diameter and then into the body of ethyl chloride to one side of the center of the vortex in the proportion of about 1 part of alloy to from 6 parts to 2 parts by weight of ethyl chloride while maintaining the ethyl chloride in the liquid state at a temperature of from about 50° C. to 90° C., and continuously removing the resulting slurry of alloy particles in ethyl chloride through the outlet substantially as fast as it is formed, and continuously passing the slurry directly to a reaction chamber while the particles of alloy are still bright.

16. The process which comprises continuously introducing a high velocity stream of liquid ethyl chloride at a temperature of from about 20° C. to about 32° C. tangentially into a quenching chamber having a restricted bottom outlet to form a rapidly whirling vortex of liquid ethyl chloride, injecting a stream of molten lead-sodium alloy, containing from 9.9% to 10.1% by weight of

40

45

sodium, at a temperature of from about 370° C. to about 750° C. through an orifice of less than $\frac{1}{8}$ inch in diameter and then into the body of ethyl chloride to one side of the center of the vortex in the proportion of about 1 part of alloy to from 9 parts to 2 parts by weight of ethyl chloride while maintaining the ethyl chloride in the liquid state at a temperature of from about 30° C. to about 65° C., and continuously removing the resulting slurry of alloy particles in ethyl chloride through the outlet substantially as fast as it is formed, and continuously passing the slurry directly to a reaction chamber while the particles of alloy are still bright.

17. The process which comprises continuously introducing a high velocity stream of liquid ethyl chloride at a temperature of from about 20° C. to about 32° C. tangentially into a quenching chamber having a restricted bottom outlet to form a rapidly whirling vortex of liquid ethyl chloride, injecting a stream of molten lead-sodium alloy, containing from 9.9% to 10.1% by weight of sodium, at a temperature of from about 370° C. to about 750° C. through an orifice of less than $\frac{1}{8}$ inch in diameter and then into the body of ethyl chloride to one side of the center of the vortex in the proportion of about 1 part of alloy to from 6 parts to 2 parts by weight of ethyl chloride while maintaining the ethyl chloride in the liquid state at a temperature of from about 30° C. to about 65° C., and continuously removing the resulting slurry of alloy particles in ethyl chloride through the outlet substantially as fast as it is formed, and continuously passing the slurry directly to a reaction chamber while the particles of alloy are still bright.

18. A process of making tetraethyl lead, which comprises quenching a molten lead-sodium alloy by introducing it into a body of cold liquid ethyl chloride held in a container at a temperature at which the ethyl chloride does not react with the quenched alloy in said container during the introduction of the molten alloy, and subsequently alkylating the lead of the unreacted, quenched alloy with liquid ethyl chloride.
